D. BRUHN

BUILDING CONSTRUCTION

Filed March 9, 1923

Daniel Bruhn
INVENTOR
BY
Victor J. Evans
ATTORNEY

UNITED STATES PATENT OFFICE.

DANIEL BRUHN, OF HOBART, INDIANA.

BUILDING CONSTRUCTION.

Application filed March 9, 1923. Serial No. 623,937.

To all whom it may concern:

Be it known that I, DANIEL BRUHN, a citizen of the United States, residing at Hobart, in the county of Lake and State of Indiana, have invented new and useful Improvements in Building Constructions, of which the following is a specification.

This invention relates to a building construction and has for its primary object a building construction wherein the major portion of the building is constructed from steel.

An object of the invention is the construction and association of various parts of steel whereby the cost of the structure is greatly reduced and besides the strength thereof greatly increased.

Besides the above my invention is distinguished in the novel manner of assembling and cutting the steel plates to form rooms and rigidly supporting the same by steel beams.

With these and other objects in view the invention will be better understood from the following detailed description taken in connection with the accompanying drawing wherein:

Fig. 1 is a diagrammatic view illustrating a portion of a building constructed in accordance with my invention.

Figs. 2 and 3 are detailed enlarged sectional views.

Again referring to the drawing illustrating one of the many constructions of my invention the numeral 1 designates a plurality of channel beams supported upon the usual brick wall 2 and in turn supporting the roof structure consisting of the angularly disposed inner connected roof beams 3. I provide a plurality of steel plates 4 which are arranged in vertical and horizontal series that abut to form a room. These plates are connected to the channel beams in a manner now to be described.

Each plate has its edge portions flanged and arranged in abutting relation as indicated at 5 and a spacer 6 is provided engaging against the flange and filling the space between the plate and channel beam 1. Bolts 7 pass through the spacer and flanges of the plate and are further connected to clamps 8 that have their end portions 9 bent over

the beam as clearly shown in Fig. 3. Thus it will be seen that the plates are rigidly secured to the beam and the beams are of such strength and positioned so as to rigidly support the plates and prevent sagging. It will be noted that the plates, besides giving accurate formation to the room, are arranged in abutting relation in such manner that heat of the room is kept in and cold air prevented from forcing its way into the room. It will also be noted that various beams used are arranged and the plates connected and associated that the strength of the building is greatly increased and besides the amount of work is greatly reduced thereby greatly reducing the cost of constructing a building.

It is, of course, to be understood that the plates may be given any shape found necessary and cut in various other manners than illustrated and besides the clamps may be constructed in various other ways and connected to the beams in other manners and, therefore, I do not desire to be limited in any manner except as set forth in the claims hereunto appended.

Having thus described my invention what I claim is:

1. In a building construction, a channel beam, metallic plates having their edges flanged and arranged in abutting relation, a spacer between the beam and plates and abutting said flanges, bolts securing the spacer to the flanges, and clamps connected to the bolts and secured over said beam.

2. In a building construction, a U shaped channel beam, metallic plates having their edges flanged and arranged in abutting relation beneath the channel beam, a spacing block disposed between the plates and the intermediate portions of the channel beam and in abutting relation with said flanged edges, a clamping plate having its ends bent over one edge of the channel beam and its other end disposed in abutting relation with the flanged edges of the plates, and securing bolts passed through the clamping plate, the flanged edges of the metallic plates and the spacer blockers for securing said elements together.

In testimony whereof I affix my signature.
DANIEL BRUHN.
